UNITED STATES PATENT OFFICE

ALBERT P. HEH, OF PITTSBURGH, PENNSYLVANIA

BRICK VENEER

Application filed November 5, 1928. Serial No. 317,269.

This invention relates to improvements in veneer construction for application to the walls of buildings, mantles, fire places, etc., and may be applied to the walls of old, as 5 well as new buildings.

An object of the invention is to provide a veneer block which may be made of any suitable material to imitate brick, tile, etc., and which is constructed so as to provide 10 mortar receiving grooves between the bricks to more closely simulate blocks laid in mortar.

Another object of the invention is the provision of a veneer block constructed so that 15 all of the blocks of a veneer wall may be secured in place before mortar is applied, so that the mortar may have a chance to properly set, and will not be dislodged by blows when securing other blocks in position.

With the above and other objects in view, 20 the invention further includes the following novel features and details of construction, to be hereinafter more fully described, illustrated in the accompanying drawings and 25 pointed out in the appended claim.

In the drawings:—

Figure 1 is an elevation showing a portion of the wall of a building with some of the blocks applied.

Figure 2 is a sectional view on the line 2—2 of Figure 1.

Figure 3 is an enlarged section on the line 3—3 of Figure 1.

Figure 4 is a detail perspective view of 35 one of the blocks.

Figure 5 is a similar view of a vertical block.

Referring to the drawings in detail where- 40 in like characters of reference denote corre- sponding parts, the block which is illustrated in Figure 4 comprises a base portion 10 and a facing portion 11. The base portion extends beyond one longitudinal edge of the facing portion as shown at 12 and beyond one transverse edge as shown at 13, the ex- 45 tended portions being of a less thickness than the body of the block and providing flanges of an appreciable width. The extended portion or flange 12 is provided with openings 12' for the passage of nails or screws.

The facing portion extends an appreciable distance beyond the opposite edge of the base portion and provides a flange 14 of less thickness than the body of the block and is transversely offset from the extended portion or 55 flange 12 as shown in Figure 3 of the drawings. The upper edge of the extended portion or flange 12 is oppositely beveled as indicated at 15 while the lower edge of the base portion is provided with a V-shaped groove 60 16. The width of the extension 14 of the facing portion 11 is less than the width of the extension or flange 12 and when the blocks are arranged as shown in Figure 3 of the drawings with the beveled edge 15 of one 65 block arranged within the V-shaped groove 16 of an adjacent block, a mortar space 17 will be provided between the blocks. Also, the extended portion 13 at the end of the block against which the next adjacent block 70 abuts will provide a vertical mortar receiv- 75 ing groove 18.

In applying the blocks to the sheathing 19 of the wall or other support, use is made of a base strip 20. This strip may be made of 80 metal or other suitable material and is screwed or otherwise secured in place as shown at 21. This strip is provided along its upper edge with opposite bevels to be received within the V-shaped groove 16 of the lowermost row of blocks. The blocks are then secured in place by means of nails 22 or other fastening devices and all of the blocks may be positioned before the mortar is applied. The mortar grooves 17 and 18 may 85 then be filled or partially filled with mortar and the mortar will not become dislodged by reason of nailing other blocks in position.

In Figure 5 of the drawings, a vertical block is shown. The construction of this 90 block is similar to the block shown in Figure 4 except that the openings 13' are placed in the end flange while the bevel 15' is provided upon the end flange and the V-shaped groove 16' at the bottom.

A corner block 23 is illustrated in Figure 2 of the drawings and this block may be constructed after the manner of the block shown in Figure 4. In other words, this corner block may have an upper extended attaching 100

flange which is disposed longitudinally of the block and an end flange so as to accommodate the other horizontally disposed blocks.

5 The invention is susceptible of various changes in its form, proportions and minor details of construction and the right is herein reserved to make such changes as properly fall within the scope of the appended claim.

10 Having described the invention what is claimed is:—

In a building construction, a veneer comprising a plurality of blocks, each block comprising a base portion and a facing portion, said base portion extending beyond one longitudinal edge and one side edge of the facing portion and defining a detaching flange, said facing portion extending beyond one edge of the base for overlapping engagement with the attaching flange of an adjacent block, said attaching flange being of greater width than the facing flange to provide mortar grooves between the opposing edges of the facing portions of adjacent blocks, one edge 15 of the attaching flange having a V-shaped groove and the opposite edge having oppositely disposed bevelled faces to engage the walls of the V-shaped groove of the adjacent attaching flanges, fasteners securing the 20 flanges to a support, and a strip receivable beneath the facing flanges of the lowermost course of blocks and having one edge provided with oppositely disposed bevelled faces to be received in the V-shaped grooves of the 25 attaching flanges of the base portions of the lowermost course of blocks.

In testimony whereof I affix my signature.
ALBERT P. HEH.
